UNITED STATES PATENT OFFICE.

OWEN E. HILL, OF NEW YORK, N. Y., ASSIGNOR TO WESTERN ELECTRIC COMPANY, OF NEW YORK, N. Y., A CORPORATION OF ILLINOIS.

DESIGN FOR A LANTERN.

48,031.

Specification for Design.

Patented Oct. 26, 1915.

Application filed May 10, 1915. Serial No. 27,275. Term of patent 14 years.

To all whom it may concern:

Be it known that I, OWEN E. HILL, a citizen of the United States, residing at New York, in the county of New York and State of New York, have invented a new, original, and ornamental Design for Lanterns, of which the following is a specification, reference being had to the accompanying drawing, forming part thereof.

Figure 1 is a perspective view of a lantern showing my new design; and Fig. 2 is a plan view thereof.

I claim:

The ornamental design for a lantern, as shown.

In witness whereof, I hereunto subscribe my name this 8th day of May, 1915.

OWEN E. HILL.
